**SINGLE ELECTRON GUN TIME SHARING
OSCILLOSCOPE**

Fred L. Katzmann, Cedar Grove, N.J., assignor to Fairchild Camera and Instrument Corporation, Syosset, N.Y., a corporation of Delaware

Filed Sept. 9, 1960, Ser. No. 55,014
16 Claims. (Cl. 315—22)

The present invention relates to time sharing oscilloscopes in which a cathode ray tube having a single electron gun is employed. A variety of waves are displayed on the face of the tube by means of switching from one wave to another and from one sweep speed to another. Thus, the single electron beam is used to display different waves successively.

An objection to time sharing oscilloscopes used heretofore is that in many instances the trace of one wave was intense whereas that of the other was dim due to the fact that the electron beam slowly crossed the tube in one case, and rapidly crossed the tube in the other. In my invention this disadvantage is eliminated since when switching from one signal source to the other I provide means for simultaneously switching from one bias level to another so that the bias of the grid or cathode of the cathode ray tube is varied in accordance with the desired setting thereby making it possible to adjust the tube trace intensities to be equal, or to have other desired relationship. My invention although described in copending application entitled "Direct Read-Out System for Oscilloscopes" (in the name of Bernard L. Hegeman, Serial No. 34,124, filed June 6, 1960, and assigned to the assignee of this application), as applicable to varying the intensity of index and readout dots relative to a display is likewise applicable to those situations in which it is desired that two completely unrelated electrical waveforms be displayed on the face of a single tube; to those situations where it is desirable to display a single waveform on different time bases; or to the display of different waveforms on the same time base.

It is an object of this invention to produce two related or unrelated electrical waveform displays in time shared, alternate sequence on a single gun oscilloscope, said displays being of varying amplitude and on different time bases, the intensity of said displays being adjustable in any desired manner.

It is another object of my invention to present a display wave to be measured alternately with a second display wave, which may for example be a rectangular wave to produce readout dots, the first and second display waves being presented at adjustable relative intensities, adjustment being effected by prior adjustment of the bias level applied to the control unit of the cathode ray tube according to the alternate presentations of the two display waves (or display wave and readout dots). It is understood of course that the waves are visible simultaneously on the cathode ray tube screen.

It is another object of the invention to blank the second or dot producing display wave, i.e., reduce its intensity to zero during the vertical and overshoot portions thereof in order to eliminate "tails" on the dots.

It is still another object of the invention to provide a single gun oscilloscope in which the intensities of related displays may be adjusted. Thus, if an electrical waveform is to be displayed on a given time base, and a portion of that waveform is to be shown on an expanded scale in the second of two presentations, this may be done and the portion selected produced with increased (or decreased) intensity in the first presentation. The portion to be enlarged can be picked out readily from the first small scale presentation, and it will be known that this

2

particular portion is the portion enlarged on the large scale presentation.

Other objects and features of the invention will be clear when the following description is considered in connection with the annexed drawings in which,

FIGURE 1 is a block diagram of a single gun oscilloscope having two switches for alternately displaying two displays on the same tube, while at the same time having those two displays in a correct intensity relationship due to the provision of a third switch which switches the bias level of the cathode ray tube to produce the correct intensities; and

FIGURE 2 is a detailed schematic circuit of the means for adjusting the relative intensities of alternately displayed patterns, and the means for switching to produce these relative intensities alternately.

Referring now to FIGURE 1, 101 and 102 are independent and unrelated display waves. Waves 101 and 102 are applied respectively to two push-pull D.C. amplifiers 103, 104 through input pairs of push-pull terminals 109, 110. Display waves 101, 102 are amplified by amplifiers 103, 104 and are applied to pairs of output conductors 133, 143 and 134, 144 respectively. Synchronizing signals 147 and 148 having periods designated T, t respectively, are derived from waves 101, 102 by well known differentiating circuits in amplifiers 103, 104 and are applied to input conductors 153, 154 of synchronizing amplifiers 105, 106 respectively.

Output conductors 145, 146 of amplifiers 105, 106 are connected to conventional triggered sweep generators 107, 108 to generate sweep waves 119, 120 with periods T, t respectively. Output conductors 135, 136 are connected to a switch the arm 125 of which is usually placed in contact with the conductor 135, 136 associated with the display wave 101, 102 having the longest period T in order to synchronize a master clock square wave multivibrator 111.

The master clock 111 comprises a multivibrator which generates a pair of out-of-phase square switching waves 112, 113, having a period 2T and applies these to conductors 131, 132 respectively to connect the switching waves to the three switches 114, 115, 116.

Switch 114 is the vertical or Y-axis switch which is supplied with two pairs of push-pull input signals from outputs 133, 143 and 134, 144 of push-pull display wave amplifiers in channels A and B respectively.

Thus, displays 101, 102 are caused to appear alternately and repetitively at push-pull output conductors 151, 152 by the coaction of switch waves 112 and 113, 50 which are applied to grids 183 and 184 also, where they cause anodes 185 and 186 of triodes 181 and 182 to alternate oppositely in potential level. The input conductors 191 and 192 to push-pull amplifier 128 are connected to anodes 185 and 186 and thus receive biases determined 55 by the adjustment of potentiometer 137 which controls the anode currents through resistors 187 and 188 when grid 183 or 184 is made positive. This action occurs at the rate of $\frac{1}{2}T$ times per second. This alternating bias is for the purpose of "trace separation" between the displays from channels A and B, which displays also occur alternately and repetitively at $\frac{1}{2}T$ times per second.

Thus, when signals over channel B are being transmitted to the vertical (Y-axis) push-pull D.C. amplifier 128 to produce deflection waves 102 at vertical plates 121, 122, plate 121 is biased positively with respect to plate 122 and when signals over channel A are being transmitted plate 122 is biased positively with respect to 121. As a result, the displays 101 and 102 are shifted on tube face 100 relative to each other. The amount of shift depends 70 on the adjustment of 137.

Each of sweep generators 107, 108 has at least three

outputs. These are respectively: linear time base sweep waves 119, 120 on conductors 139, 130; positive going brightness waves 161, 162 on conductors 159, 150; and negative going blanking waves 117, 118 on conductors 149, 140. The sweep waves 119, 120 are applied to the H (X-axis) switch 115, and the brightness waves 161, 162 and blanking waves 117, 118 are applied to the I (Z-axis) switch 116.

Coaction between the various waves generated in channels A and B, and the master clock switch wave outputs 112, 113 at the three switches 114, 115, 116, produces alternate and repetitive displays of waves 101, 102 on tube face 100. Two successive displays occur with a periodicity 2T, each display occupying a portion of time interval T. Each display is brightened during the "trace" time of its respective sweep wave, and blanked during the "retrace and dead time" of that sweep wave. The displays may be superposed or separated vertically by adjustment 137; or, horizontally, by the customary sync phase control 163 of sweep generator 103, in the usual manner for triggered sweep generators; or both.

Referring now to FIGURE 2, an arrangement is shown illustrating another use of my invention. Display wave 200 of period T' has a section S which it is desired to examine in detail while (at the same time) examining 200. Wave 200 is applied to both pairs of terminals 109, 110. Switch arm 165 disconnects sweep generator 103 from normal sync output 146 (see also FIG. 1) and connects it to output 164 of sweep generator 107 in order to synchronize 108 with the 107 sweep instead of with the display wave 200. This is in preparation for a delayed sweep observation.

This type of operation wherein a delayed portion of a sweep is used to initiate a second, or delayed, sweep is well known in the art, one method of such initiation being described in U.S. Patent No. 2,825,848, in the name of R. F. Casey.

A delaying sweep switch 173 is provided on sweep generator 107. This switch when operated causes sweep wave 219 to act as a "delaying sweep" in the manner described in detail in the above-mentioned Casey patent. In brief a synchronizing signal is derived from a portion S of wave 219 and applied through potentiometer 169, conductor 164, and switch arm 165 to sweep generator 108.

As in the Casey patent adjustment of potentiometer 169 determines the starting point 202 at which sweep generator 108 is triggered and adjustment of 203 determines the termination of sweep wave 220 generated by sweep generator 108 at a time such as 204. The duration S of sweep wave 220 thus is made to correspond to a desired portion S of sweep wave 219.

In order to produce the two separate but related displays 200, 201 on tube face 100, where display 201 is an expanded view of the brightened portion S of display 200, the display wave 200 is amplified in amplifiers 103, 104 and applied over output conductor pairs 133, 143 and 134, 144 to the input of the V switch 114 as described above for FIGURE 1. At the same time the delaying sweep 219 and the delayed sweep 220 are applied to the input of the H switch 115.

The V switch and the H switch are controlled by switch waves 212, 213 to cause the display wave 200 to be displayed on two time bases, namely the regular sweep 219 and the delayed sweep 220.

At the time when the positive going portion 214 of switch wave 212 is applied to the V switch and the H switch and to the anode of diode 221 to make cathode follower tube 205 conductive in the I (intensity) switch structure 116, the negative portion 211 of switch wave 213 is applied to the anode of diode 222. Thus, no positive potential is applied to grid 208 of cathode follower 205 at this time. The cathode follower 205 remains in a cut-off condition due to positive bias developed on cath-

ode resistor 230 by the positive wave peak 214 on grid 207. Thus, all potentials from diodes 224, 226, 228 are ineffective to produce outputs at 230 for transmission on conductor 170 for application to cathode ray tube 126 (FIGURE 1) and these potentials cannot modulate the cathode ray tube beam 171 during the first half cycle time T' of switch wave 212.

During this same time, however, a positive bias from potentiometer 229 is applied to the anode of diode 227 and is applied to grid 207 and by cathode follower action of tube 205 controls the intensity level of beam 171. This type of intensity gate is described in a copending application by Fred L. Katzmann, Serial No. 800,337, now Patent No. 2,997,620, assigned to the same assignee.

Switch 173 also causes a brightening wave 174, of duration S, in synchronism with T' but shorter than T', to be applied to the anode of diode 223 via output conductor 159. Positive portions of brightening wave 174 are applied to grid 207 and appear on conductor 170 and grid 128 to increase the beam 171 and intensify the portion S of display 200 on tube face 100. A blanking wave 175, of duration B, corresponding to the retrace and dead-time of sweep wave 219 may be applied to the cathode of diode 223, if desired, to cut-off beam 171 during the retrace and dead time of sweep wave 219.

When the positive going portion 215 of switch wave 213 is applied to the anode of diode 222, tube 205 becomes conductive and 205 becomes non-conductive. Thus, the brightening, blanking and bias potentials associated with sweep 220 are applied to control the intensity of beam 171, when sweep 220 is switched to the H deflection plates 123, 124 in place of sweep 219 by the heretofore described action of the H switch 115. During the second half period 210 of the wave 212, the intensity signals applied to grid 207 are made ineffective by cut-off action on cathode follower 205.

It will be clear to those skilled in the art that dot producing waves and their associated brightening, blanking and bias potential may be applied to the H, V and I switches, as described in Patent No. 2,997,620 referred to above, or any other waves related or unrelated to display waves 101 or 200 as described herein may, by means of a multi-contact switch, be selected and applied to the H, V and I switches, to produce a variety of displays.

For example, when a display wave 200 is to be measured quantitatively by means of read-out dots on an oscilloscope equipped with a direct read-out system switch, the display wave 200 is displayed with the dots 270, 271 instead of with the expanded section 281. To accomplish this, the switch arms 243, 244, 247, 248, 249 of the system switch are manually and simultaneously placed in positions indicated as 260 in FIGURE 2.

When the switch arms are in this position a vertical read-out wave V and its base level are applied to the V-switch arms 243, 244 respectively, and a horizontal read-out wave H with its base level is applied to H-switch arm 247. These waves are generated in generator 241 which may be of the type shown at 400 in copending application Serial No. 34,124.

A free running unsymmetrical multivibrator 240 which produces an output pulse 250, at a mean frequency of 756 cycles for example as shown at 403 in the above copending application, synchronizes generator 241 at 383 cycles. The pulse width of waves 250 is made adequate to include the rapidly moving portions 257 of the read-out waves. Waves 250 are applied to switch arm 248 and provide beam blanking during the rapidly moving "tails" between the dots.

While I have described preferred embodiments of my invention it will be understood that many modifications and variations are possible. I wish therefore to be limited not by the foregoing description but solely by the claim granted to me.

What is claimed is:

1. In a display device having elements to produce a

single light spot, in combination, means for applying first and second deflecting fields of different frequencies to deflect said spot in a first direction, means for applying a field to deflect said spot in a second direction, first switch means for alternately applying said first and second fields, thereby to develop two independent traces in time sharing sequence; second switch means to adjust the intensity of the spot to either of two selected constant levels throughout a trace interval; and means for actuating said two switch means in synchronism, whereby the intensity of said spot throughout one trace may be adjusted independently of the intensity of the spot throughout the other trace.

2. In a cathode ray oscilloscope having a single cathode ray tube with at least one electron beam, in combination, two beam deflecting means for producing a two dimensional display, means to alternately apply two deflection waves of different frequencies to one of said beam deflecting means, means to alternately apply two corresponding deflection waves of different frequencies to the other of said beam deflecting means, means to derive beam intensifying waves synchronous with the first and second of said deflection waves, means to apply said derived waves to intensify the electron beam, and switch means to simultaneously effect said alternate application of deflection waves to said one and said other deflecting means and the alternate application of said derived waves to intensify said beam.

3. In a cathode ray oscilloscope having at least one electron beam with a control electrode therefor and first and second beam deflection means for developing fields substantially at right angles to one another, in combination, means for applying first and second waveforms to be displayed alternately to the first deflection means for alternately producing two first fields, two corresponding sweep generators for applying sweep waves to the second deflection means for alternately producing two second fields, means to derive corresponding beam intensity controlling waves synchronous with said first and second waveforms, means to apply said intensity controlling waves to the control electrode to intensify the beam, and switch means to switch said corresponding display waveforms, sweep waves and intensity controlling waves simultaneously to said first and second deflection means and the control electrode, respectively.

4. In a cathode ray oscilloscope having a cathode ray tube including a fluorescent screen, at least one electron beam source and means for deflecting the beam in two directions; in combination, means for applying an electrical waveform to be analyzed to one of said deflection means and a second electrical waveform to the other of said means simultaneously to form a pattern on said screen; means to bias the beam at two intensity levels; means for generating two dot producing signals, means to apply said signals simultaneously to said deflecting means alternately with said pattern, means to modify said two dot producing signals individually to position the generated dots at selected points on said screen with respect to said waveform display and means to indicate the amount of modification of said dot producing signals to thereby indicate on one of two indicating means one coordinate dimension from one of said dots to the other and on the other of said two indicating means the other coordinate dimension from said one of said dots to the other thereof, and means to apply one of said intensity levels to bias said beam when said dots are displayed, and the other of said levels to bias said beam when said pattern is displayed.

5. In a cathode ray oscilloscope having a cathode ray tube including a fluorescent screen, a single electron beam source and the means for deflecting the beam in two directions; in combination; means for applying an electrical waveform to be analyzed to one of said deflection means and a second electrical waveform to the other of said deflection means simultaneously to form a pattern on said screen; means for generating two dot producing signals;

5 means to apply said signals to said deflection means; means to adjust the intensity of the electron beam to at least a first and a second level, switching means for applying said dot producing signals alternately with the pattern producing signals to said deflection means and means for simultaneously adjusting said intensity at said first level when said dots are produced and at said second level when said pattern is produced; means to modify said two dot producing signals individually to position the generated dots at selected points on said screen with respect to said waveform display; means to indicate the amount of modification of said dot producing signals individually to thereby indicate on one of two indicating means one coordinate distance from one of said dots to the other and on the other of said two indicating means the other coordinate distance from one of said dots to the other thereof; and means to position said waveform display together with said dots with respect to the tube screen.

6. In a cathode ray oscilloscope having a cathode ray tube including a fluorescent screen, a single electron beam source and the means for deflecting the beam in two directions; in combination; means for applying an electrical waveform to be analyzed to one of said deflection means and a second electrical waveform to the other of said deflection means simultaneously to form a pattern on said screen; means for generating two dot producing signals; means to apply said signals to said deflection means; means to adjust the intensity of the electron beam to at least a first and a second level, switching means for applying said dot producing signals alternately with the pattern producing signals to said deflection means and means for simultaneously adjusting said intensity at said first level when said dots are produced and at said second level when said pattern is produced; means to modify said two dot producing signals individually to position the generated dots at selected points on said screen with respect to said waveform display; and means to indicate the amount of modification of said dot producing signals individually to thereby indicate on one of two indicating means one coordinate distance from one of said dots to the other and on the other of said two indicating means the other coordinate distance from one of said dots to the other thereof.

7. In a cathode ray oscilloscope having a cathode ray tube including a fluorescent screen, at least one electron beam source and means for deflecting the electron beam in two directions; in combination; means for simultaneously applying an electrical waveform to be analyzed to one deflection means and a second electrical waveform to the other deflection means to form a pattern on said screen; means to apply at least two intensity levels to the electron beam; means to apply one of said intensity levels to said electron beam when said pattern is formed on said screen; means to produce a pair of phase related rectangular electrical waves of the same frequency; means to adjust the base level and amplitude of said waves individually; means for simultaneously applying one of said adjusted rectangular waves to one deflection means and the second of said rectangular waves to the other deflection means to thereby produce two dots on said screen; the position of one of said dots depending upon the base levels 55 of said waves and the position of the second of said dots depending upon the base levels and amplitudes of said waves; means to apply another of said intensity levels to said beam simultaneously with the application of said rectangular waves; and means to indicate the settings of said adjustment means to thereby directly indicate the position 60 of said other dot with respect to said one dot.

8. In a cathode ray oscilloscope having at least one electron beam and a fluorescent screen; in combination, first means to deflect the beam, second means to deflect the beam at right angles to said first means, means to control the beam intensity; means to generate a plurality of display producing waves for application to said first means; means for producing a plurality of sweep waves for application to said second means; means to derive a plurality of beam intensity controlling waves from said display pro-

ducing waves for application to said intensity control means; display switch means to select a pair from among the plurality of display producing waves, a pair from among the plurality of sweep waves and a pair from among the plurality of beam intensity controlling waves; and electronic switch means for simultaneously applying one of each of said selected pairs of waves to said first means, said second means, and said beam intensity control means, to alternately produce selected time sharing pairs of displays at selected intensity levels.

9. In a cathode ray oscilloscope having at least one electron beam and a fluorescent screen; in combination, first means to deflect the beam, second means to deflect the beam at right angles to said first means, means to control the beam intensity; means to generate a plurality of display producing waves for application to said first means; means for producing a corresponding plurality of sweep waves in synchronism with each of said plurality of display producing waves respectively for application to said second means; means to derive a plurality of beam intensity controlling waves from said display producing waves for application to said intensity control means; display switch means to select a pair from among the plurality of display producing waves, a pair from among the plurality of sweep waves and a pair from among the plurality of beam intensity controlling waves; and electronic switch means for simultaneously applying one of each of said selected pairs of waves to said first means, said second means, and said beam intensity control means, to alternately produce selected time sharing pairs of displays at selected intensity levels.

10. In a cathode ray oscilloscope having at least one electron beam and a fluorescent screen; in combination; first means to deflect the beam; second means to deflect the beam at right angles to said first means; means to control the beam intensity; means to apply a display waveform to said first means; means for producing a sweep wave of desired duration and applying said sweep wave to said second means at a predetermined time relative to said display waveform; means to produce a delayed sweep wave of a predetermined amplitude, said delayed sweep wave being initiated subsequently to said predetermined time and being of a duration shorter than said duration of said first sweep wave; means for applying said delayed sweep wave to said second means; means for deriving an intensity wave simultaneous in time with said delayed sweep wave; means for generating first and second blanking waves in synchronism with said first sweep wave and said delayed sweep wave respectively; means for applying said intensity and blanking waves to said intensity control means; and electronic switch means for simultaneously applying said display waveform, said first sweep wave, said intensity wave and said first blanking wave to said first means, said second means, and said beam intensity control means, respectively, and for alternately applying said display waveform, said delayed sweep wave, and said second blanking wave to said first means, said second means, and said intensity control means respectively to thereby make visible simultaneously a display waveform with a portion intensified and the same display waveform with said intensified portion expanded.

11. In a cathode ray oscilloscope having at least one electron beam and a fluorescent screen; in combination, first means to deflect the beam; second means to differently deflect the beam; means to intensify the beam; means to amplify display waves including a display waveform, a related portion of that waveform, an unrelated waveform, and a dot-producing square wave, and for applying said display waves to said first means; means to generate a sweep wave synchronous with each of said display waves; means for deriving blanking waves from each said display wave at a selected amplitude; means for applying said blanking waves to said beam intensifying means; display switch means to select a pair from

among said display waves, a corresponding pair from among said sweep waves, and at least one from among said blanking waves; and electronic switch means actuated synchronously with one of said pair of display waves for simultaneously applying one of each of said selected pairs of waves to said first means and said second means, and for applying at least said one of said blanking waves to said beam intensifying means alternately, to thereby produce alternately a selected pair of patterns with portions at selected intensity levels.

10 12. In a cathode ray oscilloscope having at least one electron beam and a fluorescent screen; in combination, first means to deflect the beam; second means to deflect the beam at right angles to said first means; means to control the beam intensity; means to amplify a plurality of display waveforms for application to said first means; means to apply a predetermined D.C. component to each said amplified waveform; means for producing a corresponding plurality of sweep waves each in synchronism with said display waveforms for application to said second means; means to derive a plurality of beam intensity controlling waves from said display waveforms for application to said intensity control means; display switch means to select a pair from among the plurality of amplified display waveforms having D.C. components, to select a corresponding pair from among the plurality of sweep waves and to select a pair from among the plurality of beam intensity controlling waves; and electronic switch means for simultaneously applying one of each of said selected pairs of waves to said first means, said second means, and said beam intensity control means alternately, to thereby alternately produce selected time sharing pairs of separated displays at selected intensity levels on the fluorescent screen.

15 13. In a cathode ray oscilloscope having at least one electron beam and a fluorescent screen; in combination, first means to deflect the beam; second means to deflect the beam at right angles to said first means; means to control the beam intensity; means to amplify a display waveform; means for producing a sweep wave of desired duration and applying said sweep wave to said second means at a predetermined time relative to said display waveform; means to produce a delayed sweep wave of a predetermined amplitude, said delayed sweep wave being initiated subsequently to said predetermined time and being of a duration shorter than said duration of said first sweep wave; means for applying said delayed sweep wave to said second means; means for deriving an intensity wave simultaneous in time with said delayed sweep wave; means for generating first and second blanking waves in synchronism with said first sweep wave and said delayed sweep wave respectively; means for applying both said intensity and blanking waves to said intensity control means; means to generate a square wave with a positive portion having the same duration as said sweep wave and a negative portion having said duration; means to mix said display waveform and said square wave to produce mixed waves for application to said first beam deflection means; means for applying said mixed waves to said first deflecting means; and electronic switch means actuated by said square wave for simultaneously applying said mixed waves, said first sweep wave, both said intensity wave and first blanking wave to said first means, said second means, and said beam intensity control means, respectively, and for alternately applying said mixed waves; said delayed sweep wave, and said second blanking wave to said first means, said second means, and said intensity control means respectively to thereby make visible simultaneously a display waveform with a portion intensified and the same display waveform with said intensified portion expanded and separated from said display waveform.

14. In a cathode ray oscilloscope having at least one electron beam and a fluorescent screen; in combination; a first means to deflect the beam and a second means to

deflect the beam; means to intensify the beam; means to amplify a display waveform with a first period and a display waveform with a second period; means to generate rectangular waves with a period twice that of said first period; means for mixing said display waveforms and said rectangular waves to produce first and second mixed waves for application to said first means; means to generate sweep waves synchronized with said first and second periods for application to said second means; means to derive first intensity controlling waves from said first period display waveforms and second intensity controlling waves from said second period display waveforms for application to said intensifying means; first, second, and third electronic switch means operated in synchronism by said rectangular waves for applying simultaneously said first mixed waves, said sweep waves of said first period, and said first intensity controlling waves to said first deflecting means, said second deflecting means, and said intensifying means, respectively, and alternately applying said second mixed waves, said sweep waves of said second period, and said second intensity controlling waves to said first deflecting means, said second deflecting means and said intensifying means, respectively, whereby alternate and unrelated two dimensional display patterns are produced on the fluorescent screen in time shared sequence, said display patterns being spaced apart in one dimension.

15. In a cathode ray oscilloscope having a cathode ray tube including a fluorescent screen, at least one electron beam source and means for deflecting the electron beam in two directions; in combination; means for simultaneously applying an electrical waveform to be analyzed to one deflection means and a second electrical waveform to the other deflection means to form a pattern on said screen; means to apply at least two intensity levels to the electron beam; means to apply one of said intensity levels to said electron beam when said pattern is formed on said screen; means to produce a pair of phase related rectangular electrical waves of the same frequency which rests alternately at a base level and at an amplitude level and which has rapidly moving portions between said levels; means to simultaneously applying one of said rectangular waves to one deflection means and the second of said rectangular waves to the other deflection means to thereby produce two dots on said screen; the position of one of said dots depending upon the base levels of said waves and the position of the second of said dots depending upon the base levels and amplitude levels of said waves; means to derive a blanking wave corresponding in time with said rapidly moving portions of said rectangular waves; and means to apply another of said intensity levels and said blanking wave to said beam simultaneously with the application of said rectangular waves to thereby make said beam trace invisible between said dots.

16. In a cathode ray oscilloscope having a cathode ray

tube including a fluorescent screen, at least one electron beam source and means for deflecting the electron beam in two directions; in combination; means for simultaneously applying an electrical waveform to be analyzed to one deflection means and a second electrical waveform to the other deflection means to form a pattern on said screen; means to apply at least two intensity levels to the electron beam; means to apply one of said intensity levels to said electron beam when said pattern is formed on said screen; means to produce a pair of phase related rectangular electrical waves of the same frequency which rests alternately at a base level and at an amplitude level and which has rapidly moving portions between said levels; means to adjust the base levels and amplitude levels of said waves individually; means for simultaneously applying one of said adjusted rectangular waves to one deflection means and the second of said adjusted rectangular waves to the other deflection means to thereby produce two dots on said screen; the position of one of said dots depending upon the base levels of said waves and the position of the second of said dots depending upon the base levels and amplitude levels of said waves; means to derive a blanking wave corresponding in time with said rapidly moving portions of said rectangular waves; means to apply another of said intensity levels and said blanking wave to said beam simultaneously with the application of said rectangular waves to thereby make said beam trace invisible between said dots; and means to indicate the settings of said adjustment means to thereby directly indicate the position of said other dot with respect to said one dot.
